DESIGN FOR A GAME BOARD

Paul Panhorst, Philadelphia, Pa., assignor to O.
Schoenhut, Incorporated, Philadelphia, Pa., a corporation of Pennsylvania

Application February 7, 1938, Serial No. 74,941

Term of patent 14 years

To all whom it may concern:

Be it known that I, Paul Panhorst, a citizen of the United States of America, residing at Philadelphia, in the county of Philadelphia and State of Pennsylvania, have invented a new, original, and ornamental Design for a Game Board, of which the following is a specification, reference being had to the accompanying drawings, forming part thereof, in which;

Figs. 1 and 1a are a composite plan view of a game board, showing my new design.

Fig. 2 is an edge view of the same.

I claim:

The ornamental design for a game board, as shown.

PAUL PANHORST.
